UNITED STATES PATENT OFFICE.

EDWARD H. WILLIAMSON AND TOLBERT N. RICHARDSON, OF PHILADELPHIA, PENNSYLVANIA; SAID RICHARDSON ASSIGNOR TO SAID WILLIAMSON.

LUNCH KIT.

1,420,598.

Specification of Letters Patent. Patented June 20, 1922.

Application filed November 9, 1920. Serial No. 422,816.

To all whom it may concern:

Be it known that we, EDWARD H. WILLIAMSON and TOLBERT N. RICHARDSON, citizens of the United States, and residents of Philadelphia, Pennsylvania, have invented certain new and useful Improvements in Lunch Kits, of which the following is a specification.

Our invention concerns lunch boxes or kits in which the top or cover member is provided with means for holding a thermos bottle or the like within the top, and one object of our invention is to provide an efficient form of holder which is combined with the top in such manner as to present a good appearance and not to alter or mar the general appearance of the box or kit. Other objects of the invention will be clear from the following description:

20 The invention is shown in the accompanying drawings in which—

Figure 1 is a plan view of the box with the cover or top thrown back.

Figure 2 is a detail sectional view.

25 Figure 3 is a view of a detail.

In these drawings, 1 indicates the main body of the box and 2 the cover or top section which is hinged to the body at 3. This top section is of considerable height and is adapted to receive within it a thermos bottle or the like, this bottle being supported entirely above the plane of the main body portion so as to leave this entirely available for receiving its contents, such as materials 35 making up the lunch. In order to hold the thermos bottle, the outline of which is indicated at 4, we provide a holder consisting of a wire member having the two sides 5, each of which is turned substantially at right angles at its end to form a journal 40 6. These journals find bearings in the wall of the top of cover section by pressing in the wall at the points 7. It will be noted that the two sides 5 converge from the points 45 where they are hinged or journalled to the side of the top section, and they are connected by a cross piece 8, this cross piece being a continuation of the sides 5. The cross piece is adapted to take under a locking projection 9 which is conveniently formed by pressing in the wall of the side of the top section. The cross piece 8 is of angular form, its central portion 9 lying in rear of its portions 10 where the cross piece merges into the sides 5 and this construction facilitates the engagement of the cross

piece with the locking projection on the side of the cover. The locking projection is a little shorter than the length of the cross piece and the inclines at 11 of the cross piece, when pressure is exerted to effect the locking action, will ride over the curved ends of the locking projection and thus get in position below the same so as to retain the holder in place.

65 The bearings formed by indenting the wall of the top section to receive the journals of the holder provides a simple and effective construction and one which will enable the holder to be placed in position 70 readily, and it will be observed that these indented bearing portions of the wall of the top section lie back of the members 12 which form portions of the clasps which are employed for holding the free edge of the 75 top section in connection with the main body. In other words, the top or cover section is provided with keepers 12 of these clasps and these keepers overlie and hide the bearings in which the holding member 80 is journalled, so that the appearance of the cover section is not interfered with at these points.

75 The bearings for the holder are located at widely separated points, and the sides 5 of the holder are convergent from these points towards the opposite side of the top or cover section, and by this construction widely separate bearings or engaging points are provided for contact with the thermos 90 bottle or other article which is to be carried so that this will be held firmly in position.

85 It will be understood that the above description and the drawing accompanying the same are to be regarded as illustrative 95 of our invention and not as restricting it to the precise construction disclosed, the scope of the invention being defined by the appended claims. We do not limit ourselves to the location of the bearings so 100 widely separate as illustrated nor to the form or location of the clasp means employed for holding the top or cover section closed.

105 We claim as our invention—

1. A lunch box comprising a body and a top hinged thereto, clasps for securing the top to the body, members of said clasps being mounted on the top, and a holder for a thermos bottle or the like, comprising a 110 member hinged to the free or unhinged side of the top back of the clasp members there-

on and means on the hinged side of the top to engage the free end of the holder to retain the same in place, substantially as described.

5. 2. In combination with a lunch box having a body member and a cover hinged thereto, a holder for a thermos bottle or the like, comprising a wire member having two sides with pintles journaled to one side 10 wall of the cover and connected by a cross piece of angular form with its center por-

tion receding and providing inclines 11 and a locking projection to engage the said cross bar carried by the side wall of the cover, said locking projection being shorter than 15 the cross piece of the holder so that the said inclines will ride over the ends of the projection substantially as described.

In testimony whereof, we affix our signatures.

EDWARD H. WILLIAMSON.
TOLBERT N. RICHARDSON.
